(57) **CLAIM**

The ornamental design for a light, as shown and described.

DESCRIPTION

FIG. 1 is a perspective view of the light of the present invention.

FIG. 2 is a front elevation view of the light of the present invention; the back side view is a mirror image.

FIG. 3 is a left side elevation view of the light of the present invention, rotated ninety degrees relative to FIG. 2; the right side view is a mirror image.

FIG. 4 is a top plan view of the light of the present invention; and,

FIG. 5 is a bottom plan view of the light of the present invention.

The broken lines shown on the drawings are for illustrative purposes only and form no part of the claimed design.
